Primary Examiner — Daniel J Domino*Assistant Examiner* — Samina Vieth(74) *Attorney, Agent, or Firm* — Dentons US LLP(57) **CLAIM**

We claim the ornamental design for a laser radar (LR-16F), as shown and described.

DESCRIPTION

FIG. 1 is a perspective view of a laser radar (LR-16F) showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The dashed broken lines shown in FIG. 7 illustrate environmental structures that form no part of the claimed design.
